T. R. McKNIGHT.
GATE FOR DUMP CARS.
APPLICATION FILED MAY 13, 1908.

905,222.

Patented Dec. 1, 1908.

Fig. 1.

UNITED STATES PATENT OFFICE.

THOMAS R. McKNIGHT, OF AURORA, ILLINOIS, ASSIGNOR TO WESTERN WHEELED SCRAPER COMPANY, OF AURORA, ILLINOIS, A CORPORATION OF ILLINOIS.

GATE FOR DUMP-CARS.

No. 905,222.

Specification of Letters Patent.

Patented Dec. 1, 1908.

Application filed May 13, 1908. Serial No. 432,622.

To all whom it may concern:

Be it known that I, THOMAS R. McKNIGHT, a citizen of the United States, residing at Aurora, in the county of Kane and State of Illinois, have invented certain new and useful Improvements in Gates for Dump-Cars, of which the following is a specification, reference being had to the accompanying drawings.

10 My invention relates to dump-cars of the type in which the car-body is arranged to be tilted to discharge the load at the side, such cars usually being arranged so that the load may be dumped at either side.

15 It has for its object to provide a new and improved side-gate for such cars which will be light in construction, but will possess the necessary strength and rigidity to satisfactorily answer the requirements of the service

20 in which such cars are usually employed. I accomplish this object as illustrated in the drawings and as hereinafter described.

What I regard as new is set forth in the claims.

25 In the accompanying drawings, in which I have illustrated my improved side-gate as applied to a dump-car mounted so that it may be dumped at either side of the car,—Figure 1 is a partial end view of a car, showing the car-body, the side-gates and mechanism for automatically holding up the gates when the car-body is tilted to permit of the discharge of the load; and Fig. 2 is an enlarged cross-sectional view of one of the gates.

30 Referring to the drawings,—3 indicates the car-body which is mounted on supports 4 pivoted at 5 upon the truck, as illustrated and described in Patent No. 612,263, granted 40 to me October 11, 1898.

35 6 indicates the side-gates, which, as shown in Fig. 2, are composed of two parallel plates 7—8 secured together at their side edges by Z-bars 9 oppositely arranged, the outwardly-projecting flanges 10 of said Z-bars being riveted or otherwise fixedly secured along the margins of the plate 7, while the inwardly-projecting flanges 11 of said Z-bars are secured at the side edges of the plate 8 and between the plates 7 and 8, as shown in Fig. 2. The plates 8 with the Z-bars thus reinforce the plates 7 which directly support the load, thus providing a very strong and rigid but nevertheless relatively light construction.

55 The side-gates 6, in the construction

shown, are provided with straps or arms 12—13 pivoted to the ends of the car-body at 14—15, respectively, as shown in Fig. 1, and are operated by straps 16—17, as described in my said patent,—the arrangement being such that when the car-body is tilted to dump the load at either side the end-gate at such side of the car is held up while the car-body is tilted, thereby permitting the load to discharge.

60 It will be noted that while my improved side-gates are shown and described in connection with a dump-car of the type referred to, they may be employed in other forms or other styles of cars and may also be used as end-gates, or in other equivalent situations.

65 That which I claim as my invention, and desire to secure by Letters Patent, is,—

1. The combination of a car-body, a gate comprising separated parallel plates fixedly connected together, and means pivotally connecting the end portions of the gate with the car-body so that it may be swung into and out of operative position.

70 2. The combination of a car-body, a gate comprising separated parallel plates, Z-bars rigidly connecting the side edges of said plates together, and means pivotally connecting the end portions of the gate with the car-body so that it may be swung into and out of operative position.

75 3. The combination of a car-body, a gate comprising separated parallel plates, oppositely-disposed Z-bars rigidly connecting the side edges of said plates together, and means pivotally connecting the end portions of the gate with the car-body so that it may be swung into and out of operative position.

80 4. The combination of a car-body, a gate comprising plates set a distance apart, bars secured to the side edges of said plates and serving to rigidly connect them together, and means pivotally connecting the end portions of the gate with the car-body so that it may be swung into and out of operative position.

85 5. The combination with a dump-car, of a gate comprising plates set a distance apart, bars secured to the side edges of said plates and serving to rigidly connect them together, and means pivotally connecting the end portions of the gate with the car-body so that it may be swung into and out of operative position.

90 6. The combination with a dump-car, of

a gate comprising plates set a distance apart, bars secured to the side edges of said plates and serving to rigidly connect them together, means pivotally connecting the end portions 5 of the gate with the car-body so that it may be swung into and out of operative position, and means for automatically holding the

gate out of operative position when the car-body is dumped.

THOMAS R. McKNIGHT.
